UNITED STATES PATENT OFFICE.

SHELLEY G. WOODRUFF, OF INGLEWOOD, CALIFORNIA.

ROTARY-DISK ECCENTRIC BIT.

Application filed July 1, 1925. Serial No. 40,857.

This invention relates to improvements in rotary disk bits used in well drilling operations and the like.

An object of the invention is to provide an improved type of rotary disk bit, in which the rotary disk cutters are shiftable or are capable of rotating upon axes, the positions of which may be varied or adjusted.

Another object of the invention is to provide a rotary disk bit having disk cutters rotatable about movable axes, which will permit the cutters to be lowered through a casing, and upon encountering the bottom of a well hole to expand, so that a hole may be drilled which is larger than the exterior diameter of the casing.

A further object of the invention is to provide a rotary disk bit in which the rotary disk cutters are adjustable, so that the bit may be caused to drill holes of various diameters.

With the foregoing and other objects in view which will be made manifest in the following detailed description and specifically pointed out in the appended claims, reference is had to the accompanying drawings for an illustrative embodiment of the invention, wherein:

Figure 1 is a side elevation of the improved bit, the cutters being shown in retracted position,

Fig. 2 is an end elevation of the same,

Fig. 3 is a vertical section taken on the line 3—3 of Fig. 1,

Fig. 4 is a side elevation of the bit, the cutters being shown in expanded position, and

Fig. 5 is a side elevation of a slightly modified form of construction.

Referring to the accompanying drawings wherein similar reference characters designate similar parts throughout, the improved bit consists of a body 10 having its upper end threaded, as at 11, for attachment to a drill tube. A vertical axial bore 12 is formed in the body 10, permitting circulation fluid to be discharged therethrough onto the cutters. Arms 13 and 14 depend from the body 10, and these arms are parallel and are arranged directly opposite each other. Pins or bolts 15 and 16 extend through the arms 13 and 14 and are rotatable therein. These pins or bolts are shown as provided with heads 17 which are received in the arms 13 and 14, and with screws or threaded shanks 18. Eccentrics 19 and 20 are threaded onto the threaded shanks 18 and are tightened against the

bodies of the pins or bolts 15 and 16 respectively. Each of the eccentrics is provided with a peripheral shoulder or flange 21, which serves to maintain the disk cutters 22 and 23 upon their respective eccentrics 19 and 20 by permitting the disks to rotate on the eccentrics.

In the modification shown in Figs. 1 to 4 inclusive the eccentrics 19 and 20 carry pins 24, which slidably engage upon the lower ends of the arms 13 and 14. These pins are engageable upon stops 25 formed on the arms, so that the rotational movement of the eccentrics is limited.

By the improved construction it will be readily appreciated that as the bit is lowered into a hole, it may readily pass through the casing in the collapsed position shown in Fig. 1, in which the axes of the cutters are nearly in alignment. As the cutters engage the bottom of the hole, they will cause the eccentrics and the pins or bolts 15 and 16 to turn, so that the cutters will then assume the position shown in Fig. 4, which is the expanded position of the bit. It will be readily appreciated that upon rotation of the bit, the cutters, while in this position, will cut a hole of larger diameter than the diameter of the casing, through which the bit has passed. When it is necessary to pull the bit from the hole, the upward movement will allow the eccentrics to return to the position shown in Fig. 1, permitting the bit to be withdrawn through the casing. In the modification of the bit as above described, there are only two stops engageable upon the pins 24 for limiting the movement of the eccentrics.

In the modification shown in Fig. 5, a series of apertures 26 is formed in each of the arms, and pins 27 are insertable in either of the apertures and are engageable upon the eccentrics. By this construction the rotary disks 22 and 23 can be caused to be maintained in the fully collapsed position or in expanded position or in a position therebetween. In this manner the bit may be caused to drill holes of various diameters, depending upon which hole 26 the pin 27 is positioned in.

A somewhat unobvious advantage of the improved construction, employing the eccentrics, resides in the fact that this permits the depending arms 13 and 14 to be positioned directly opposite each other, as distinguished from cutters heretofore employed, in which the arms 13 and 14 are somewhat offset with respect to each other. Although the arms 13

and 14 are directly opposite, the pins or bolts 15 and 16 pass through their centers, and at the same time the disks rotate upon axes which are located other than through the centers of the arms 13 and 14. Because of the fact that the arms are directly opposite, instead of offset, the space within the hole occupied by the body of the bit during rotation is smaller than in bits having the offset arms.

10 It will be understood that various changes in the detail of construction may be made without departing from the spirit or scope of the invention as defined by the appended claims.

15 I claim:

1. A rotary disk bit comprising a body having depending arms, members rotatable upon said arms, eccentrics detachably secured to said members, and disk cutters rotatable upon 20 said eccentrics.

2. A rotary disk bit comprising a body having depending arms, members rotatable upon said arms, eccentrics secured to said members, disk cutters rotatable upon said eccentrics, 25 and means permitting but limiting rotational movement of said members upon said arms, whereby the bit may be lowered into a well hole with the cutters in contracted positions, and upon encountering the bottom of the hole 30 they may move into expanded positions.

3. A rotary disk bit comprising a body having a pair of spaced depending arms and a vertical bore adapted to discharge circulation fluid centrally of the space between said 35 arms, members rotatably mounted upon said arms, flanged eccentrics threaded onto said members and disposed against the opposed faces of said arms, and disk cutters rotatably mounted upon said eccentrics.

40 4. A rotary disk bit comprising a body having a pair of spaced depending arms and a vertical bore adapted to discharge circulation fluid centrally of the space between said arms, members rotatably mounted upon 45 said arms, flanged eccentrics threaded onto said members and disposed against the opposed faces of said arms, disk cutters rotatably mounted upon said eccentrics, and means permitting but limiting the rotational movement of said members as and for the purpose 50 described.

5. A rotary drill bit comprising a body

having a pair of depending spaced arms, eccentrics rotatably mounted upon the bit adjacent the inner opposed faces of the arms, 55 and disk cutters rotatable upon the eccentrics, the space between the cutters being unobstructed.

6. A rotary drill bit comprising a body having a pair of depending spaced arms, eccentrics rotatably mounted upon the bit adjacent the inner opposed faces of the arms, disk cutters rotatable upon the eccentrics, and means connecting each eccentric to the arm on which it is rotatable for preventing rotation of the eccentric in at least one direction. 60

7. A rotary drill bit having a pair of depending spaced arms, pins extending through the arms, eccentrics which are detachable from the pins mounted thereon adjacent the 70 arms, said eccentrics being rotatable relatively to the arms, means limiting the rotational movement of the eccentrics, and disk cutters rotatable upon said eccentrics.

8. A rotary drill bit comprising a body having a pair of depending spaced arms, eccentrics rotatably mounted upon the bit adjacent the inner opposed faces of the arms and disk cutters rotatable upon the eccentrics, the space between the cutters being unobstructed, one side of each cutter bearing against the inner face of its respective arm. 75

9. A rotary drill bit comprising a body having a pair of depending spaced arms, eccentrics rotatably mounted upon the bit adjacent the inner opposed faces of the arms, disk cutters rotatable upon the eccentrics, and means connecting each eccentric to the arm on which it is rotatable for limiting rotation of the eccentric in at least one direction, each cutter having one side bearing against the inner face of its respective arm. 80

10. A rotary drill bit comprising a body having a pair of depending spaced arms, disk cutters rotatably mounted upon the inner opposed faces of the arms, the space between the cutters being unobstructed, each cutter having one side bearing against the inner face of its respective arm, and means permitting movement of the axis of rotation of the 90 cutters relatively to the arms. 100

In testimony whereof I have signed my name to this specification.

SHELLEY G. WOODRUFF.
